UNITED STATES PATENT OFFICE.

IRVING A. MOORE, OF TRENTON, NEW JERSEY.

WASHBASIN.

1,056,352.

Specification of Letters Patent. Patented Mar. 18, 1913.

Application filed November 15, 1911. Serial No. 660,313.

To all whom it may concern:

Be it known that I, IRVING A. MOORE, a citizen of the United States, residing at Trenton, in the county of Mercer and State 5 of New Jersey, have invented new and useful Improvements in Washbasins, of which the following is a specification.

The invention relates to wash basins, and has for its primary object to provide a wash 10 basin in which the waste plug will be concealed from view and may be readily and easily raised for the discharge of the contents of the basin, and also lowered for allowing the filling thereof, without possibility of the overflowing of the contents 15 therefrom.

A still further object of the invention is the provision of a wash basin which is simple in construction, thoroughly sanitary, reliable and efficient in operation, and inexpensive in manufacture.

With these and other objects in view, the invention consists in the construction, combination and arrangement of parts, as will 25 be hereinafter more fully described, illustrated in the accompanying drawings, and pointed out in the claim hereunto appended.

In the drawings: Figure 1 is a vertical sectional view through the wash basin constructed in accordance with the invention, the section being taken in the plane of its overflow. Fig. 2 is a sectional view on the line 2—2 of Fig. 1.

Similar reference characters indicate corresponding parts throughout the several views of the drawings.

Referring to the drawings by numerals, the wash basin comprises a bowl 5, which is of the usual shape and constructed from 40 suitable material having a top flange 6 which extends circumferentially about the said bowl, the flange being formed with a down-turned outer rim 7 which is coextensive with the top flange. Provided centrally in 45 the bottom of the bowl 5 is a discharge orifice or aperture 8, in which is suitably fitted a foraminous strainer disk 9, and this orifice or aperture 8 communicates or opens into an overflow channel 10 which is carried upwardly at the rear of the bowl to the top flange 6 thereon.

Formed in the channel 10 is a solid partition 11 which extends upwardly therein and terminates spaced from the top flange 55 6 for separating the discharge channel 12 from the overflow channel 10, the discharge

channel 12 being in alignment with the overflow channel, and by reason of the termination of the partition spaced from the top flange 6 on the bowl, the said channels will 60 be in communication with each other near the said top flange, whereby on the filling of the bowl to a predetermined level and such filling thereof exceeds this level, the overflow will be conveyed into the discharge 65 channel 12 for its delivery to a waste pipe.

The waste pipe 13 intersects the discharge channel 12 and is connected both with the partition 11 and the wall of the said discharge channel by means of union rings or 70 nuts 14 ordinarily used, the waste pipe 13 being cut away in one side to form an opening 15 communicating with the discharge channel 12, so that the overflow therein will be delivered into the said waste pipe, so 75 that it may be carried off in the usual manner through a sewerage system.

The waste pipe 13, at the inner end flush with the partition 11, is formed with a valve seat 15, in which is normally engaged 80 a plug 16, the same being formed with a depending stem 17, to which is loosely connected the eye terminal 18 at one end of a plug operating rod 19, the same being slightly outwardly bowed and extends upwardly toward the top flange 6 of the bowl 85 and is connected with a hand operated knob, presently described. The plug 16 is adapted to close the pipe 13 and is mounted to work exteriorly of the body 5 so as not to 90 protrude into the discharge aperture 8 when moving to opening or closing position.

The top flange 6 in alignment with the channels 10 and 12 is provided with a thimble 20, the same being suitably mounted in 95 the top flange, and in which is engaged the hand operated knob, comprising a hollow cylindrical body 21, open at its outer end, while provided in its opposite closed end is a central aperture 22, through which is 100 passed the operating rod 19, the latter being formed with a series of transverse openings 23 for adjustably receiving a pin 24, so that the rod may be adjusted with respect to the body 21, whereby the plug may be properly 105 seated. Detachably threaded on the body 21 is a hand grip or cap 24 which permits the ready manipulation of the knob and closing of the plug 16, as well as enabling access to the interior of the body 21, so as to 110 adjust the pin 24 for regulating the rod 19, whereby the plug may be properly seated.

Mounted in and projecting outwardly from diametrically opposite points of the body 21 are holding lugs, which latter are designed to engage in vertical slots 26 formed in diametrically opposite sides of the thimble 29, the lugs, when engaged in the slots, holding the plug 16 seated for the closing of the bowl. Upon lifting the cap on the body 21 and turning the latter, the lugs will engage the upper peripheral edge of the thimble after leaving the slots 26 therein, thereby raising the plug 16 for opening the discharge pipe, so that the contents of the bowl may be drained therefrom.

15 It is clearly evident that the bowl can only be filled to a predetermined level, and any excess will overflow through the channels 10 and 12 into the waste pipe 13. When the water in the bowl has reached a predetermined level therein, it will effect a water seal in the pipe 10, so as to obviate the entrance of sewer gas or other obnoxious fumes through the bowl to a room, as well as obviating the possibility of the impregnating of the water with such fumes, thereby rendering the bowl sanitary.

20 From the foregoing, taken in connection with the accompanying drawings, it is

thought that the construction and operation of the invention will be readily understood, so without requiring a more extended explanation.

What is claimed is:

In combination with a basin body having an unbroken surface provided with a discharge port, said body being also provided with a compartment having a partition therein for forming sub-compartments, of a waste pipe connected to the outer wall of said compartment and to said partition and in alinement with said discharge port, a step plug normally seated in the end of said pipe and being adapted to work exteriorly of said body so as not to protrude into said discharge port when moving to opening or closing position, and means mounted in said body and extending through one of said sub-compartments for operating said plug.

In testimony whereof I affix my signature in presence of two witnesses.

IRVING A. MOORE.
